(57) **ABSTRACT**

A method for manufacturing a label with a hanging handle includes providing a first laminated material having a backing layer and a first frontal layer having a frontal surface, coating the frontal surface with a layer of release promoter, leaving a free zone, providing a second laminated material having a second frontal layer and having a predefined thickness and an adhesive layer, joining the first and second laminated materials to form an assembled component, cutting a hanging handle in a handle zone of the second laminated material only to the inside of the thickness of the second laminated material, leaving the first frontal layer intact, cutting a secondary label in a secondary label zone within the thickness of the second laminated material, forming a label outline in the first frontal layer, and removing a portion of the first frontal layer, creating a cavity that arranges a handle portion of the hanging handle.

LABEL AND MANUFACTURING METHOD

CROSS-REFERENCE TO RELATED APPLICATIONS

This application is a National Phase Application of PCT International Application No. PCT/IB2020/054192, having an International Filing Date of May 4, 2020 which claims priority to Italian Application No. 102019000006478 filed May 2, 2019, each of which is hereby incorporated by reference in its entirety.

FIELD OF THE INVENTION

The present invention relates to a method for manufacturing a label with a handle for hanging a bottle in an upside-down position, and a label with a handle which can be obtained by such method.

BACKGROUND OF THE INVENTION

A label with a handle applicable to a bottle is illustrated in prior art document EP0356574A2 in which such handle protrudes free from the upper edge of the label when it is not in use.

Such solution has the main disadvantage of being technically complex and costly. Further solutions of this type are known, for example, from US 2006/057313 A1, U.S. Pat. Nos. 5,878,901 A, 5,135,125 A, CN 201 685 500 U.

A similar solution is disclosed in US2006057313. FIG. 2b of this document shows that layers cut through their entire thickness are arranged on a silicone-coated backing layer, indicated here by reference numeral 10, to obtain a handle which rests entirely on the silicone-coated backing layer.

Document WO2018220660 shows a label consisting of a single layer resting on a silicone-coated backing layer (indicated by reference numeral 5 in FIG. 5 of this document). A supporting handle is cut into this single layer and rests entirely on this silicone-coated backing layer.

A label with a handle made by joining two separate adhesive films is known instead from prior document EP2246266A1, by the same owner.

As shown in such document, a lower film comprises the wording required to identify the infusion container, while a transparent upper film is joined in an adhesive manner to the lower film and makes the handle for turning the container up-side-down when administering its contents to a patient.

A drawback related to this prior technique is that, when the label is applied to a bottle, any printed characters placed on the surface tend to be damaged due to the mechanical stresses to which the bottle and the label are subjected at the labeling machine.

A further drawback related to this prior technique relates to the limited extension of the handle with respect to the width or height of the adhesive label, a limit which, in the case of small bottles, makes the handle unusable or difficult to use to suspend the bottles to which it is applied.

Furthermore, the need is strongly felt to have a handle label with separable secondary labels to identify the product contained in the bottle also in a separate document, separating at least one of these secondary labels, e.g. with pre-printed product indications, and applying it to the separate document, e.g. a medical record.

SUMMARY OF THE INVENTION

The present invention provides a method and a self-adhesive label capable of overcoming the drawbacks described with reference to the prior art.

2

In particular, the method and label according to the present invention have been designed to make the hanging handle simple to make and easy to use even if the container to which it is applied is small. Additionally, the method and label according to the present invention are designed to make the secondary label print characters resistant to abrasion forces. Furthermore, according to an advantageous aspect of the present invention, the secondary label is designed to be writable on the surface using ordinary writing instruments.

BRIEF DESCRIPTION OF THE FIGURES

15 The object of the present invention will now be described in detail, with reference to the appended drawings, in which:

FIG. 1 diagrammatically shows a manufacturing method, which is the object of the present invention, according to a possible embodiment;

20 FIGS. 2, 5, 7, 11, 14, 16 show views of multi-layer material at the positions marked by numbers II, V, VII, XI, XIV, XVI in FIG. 1, in the direction of the arrow shown, respectively;

FIGS. 3, 4 show a section view taken along the plane shown in FIG. 2 and along the plane IV-IV shown in FIG. 1, respectively;

25 FIG. 6 shows a section view taken along the plane VI-VI indicated in FIG. 5;

FIGS. 8, 9, 10 show sections taken along the planes VIII-VIII, IX-IX, X-X in FIG. 7, respectively;

30 FIGS. 12A, 12B, 12C, 13 and 13B show sections taken along the planes XII-XII, XIII-XIII in FIG. 11, respectively, in which the arrows diagrammatically show the depth of separation, cutting or die-cutting through the illustrated materials and in which the views show the sections before and after the removal of die-cutting scraps;

FIG. 15 shows a section view taken along the plane XV-XV indicated in FIG. 14; and

35 FIGS. 16 and 17 diagrammatically show a front view and an axonometric view of a label according to the present invention, according to a possible variant, in which the gripping portion of the handle and a portion of the secondary label are partially raised.

45 DETAILED DESCRIPTION

In accordance with a general embodiment, the aforesaid objectives are achieved through a method for manufacturing a label 1 with a hanging handle 2 which comprises the steps of:

- i) providing a first laminated material 4 comprising a backing layer 6 and a first frontal layer 8 joined in a releasable manner, wherein the first frontal layer 8 comprises a frontal surface 10;
- ii) coating the frontal surface 10 of the first frontal layer 8 with at least one layer of release promoter 12, 18, leaving a free zone 14 from which the at least one layer of release promoter 12, 18 is missing;
- iv) providing a second laminated material 20 comprising a second frontal layer 28 and an adhesive layer 26', wherein the second laminated material 20 has a pre-defined thickness S1;
- v) joining the first laminated material 4 and the second laminated material 20 to form an assembled component or laminated material 40, so that the adhesive layer 26' of the second laminated material 20 adheres at least to the free zone 14 of the first laminated material 4; and

vii) cutting a hanging handle 2 in a handle zone 16 of the second laminated material 20 only to the inside of the thickness S1 of the second laminated material 20, leaving the first frontal layer 8 intact; cutting at least one secondary label 34 in a secondary label zone 36 different from the handle zone 16 only within the thickness S1 of the second laminated material 20; forming a label outline 38 in the first frontal layer 8, avoiding cutting the hanging handle 2 and removing a portion of the first frontal layer 8 thus creating a cavity 95 which arranges a handle portion 96 of the hanging handle 2, with the label formed, overhangingly protruding beyond the label outline 38.

In accordance with a general embodiment, the aforesaid objectives are achieved through a method for manufacturing a label 1 with a hanging handle 2 which comprises the steps of:

- i) providing a first laminated material 4 comprising a backing layer 6 and a first frontal layer 8 joined in a releasable manner;
- ii) coating a frontal surface 10 of the first frontal layer 8 with at least one layer of release promoter 12, 18, leaving a free zone 14 from which the at least one layer of promoter 12, 18 is missing;
- iii) providing a second laminated material 20 comprising a second frontal layer 28 and an adhesive layer 26';
- v) joining the products of steps ii) and iv) to form a coupled material 40, so that the adhesive layer 26' adheres at least to the free zone 14 of the first laminated material 4; and
- vii) at least in the thickness S1 of the second laminated material 20, separating a hanging handle 2 from the handle zone 16, and at least one secondary label 34 from the label 1 in a different zone 36, and forming a label outline 38 in the first frontal layer 8 so that the hanging handle 2, with the label formed, protrudes at least partially overhangingly beyond the label outline 38.

According to a general embodiment, a label 1 with a hanging handle 2 which can be obtained through the method according to the preceding embodiment, comprises:

a first laminated material 4 comprising a backing layer 6 and a first frontal layer 8 joined in a releasable manner, wherein the first frontal layer 8 comprises a frontal surface 10; at least one layer of release promoter 12, 18, which coats a frontal surface 10 of the first frontal layer 8 leaving free a zone 14 in which the at least one layer 12, 18 of release promoter is missing;

a second laminated material 20 comprising a second frontal layer 28 and an adhesive layer 26', the second laminated material 20 being joined to the first laminated material 4 so that the adhesive layer 26' adheres at least to the free zone 14, wherein the second laminated material 20 has a predefined thickness S1;

wherein the second frontal layer 28 delimits a hanging handle 2 and a secondary label 34 in a different zone 36 of the second frontal layer 28, and wherein the first frontal layer 8 forms a label outline 38 leaving the hanging handle 2 with a handle portion 96 protruding at least partially overhanging beyond the label outline 38 outside the first frontal layer 8 directly facing the backing layer 6, thus forming a cavity 95 in which a portion of the first frontal layer 8 has been removed.

According to a general embodiment, a label 1 with a hanging handle 2, which can be obtained through the method according to the preceding embodiment, comprises:

a first laminated material 4 comprising a backing layer 6 and a first frontal layer 8 joined in a releasable manner; at least one layer of release promoter 12, 18, which coats a frontal surface 10 of the first frontal layer 8 leaving free a zone 14 in which the at least one layer 12, 18 of release promoter is missing;

a second laminated material 20 comprising a second frontal layer 28 and an adhesive layer 26', the second laminated material 20 being joined to the first laminated material 4 so that the adhesive layer 26' adheres at least to the free zone 14;

wherein the second frontal layer 28 delimits a hanging handle 2 and a secondary label 34 in a different zone 36 of the second frontal layer 28, and wherein the first frontal layer 8 forms a label outline 38 leaving the hanging handle 2 protruding at least partially overhanging beyond the label outline 38 outside the first frontal layer 8.

In accordance with an embodiment of the method, the aforesaid objectives are achieved through a method for manufacturing a label 1 with a hanging handle 2, comprising the steps of:

- i) providing a first laminated material 4 comprising a backing layer 6 and a first frontal layer 8 joined in a releasable manner;
- ii) coating a frontal surface 10 of the first frontal layer 8 with at least one layer of release promoter 12, 18 (e.g. a silicone paint) leaving a free zone 14 from which the at least one layer of promoter 12, 18 is missing;
- iii) optionally coating with registration a handle zone 16 of a first layer of release promoter 12 with a second layer of release promoter 18 in liquid or semi-liquid form;
- iv) providing a second laminated material 20 comprising a second frontal layer 28 which is transparent to light and an adhesive layer 26';
- v) joining the products of steps ii) and iv) or of steps iii) and iv) to form a coupled material 40, so that the adhesive layer 26' adheres at least to the free zone 14 of the first laminated material 4 (in particular, to form an anchoring foot 46);
- vi) optionally solidifying or cross-linking the second layer of release promoter 18 in contact with the adhesive layer 26' of the second laminated material 20, to bond such layers 18, 26'; and
- vii) at least in the thickness S1 of the second laminated material 20, separating ("cutting out" according to a variant) a hanging handle 2 from the handle zone 16 at least one secondary label 34 of such label 1 in a different zone 36 (different with respect to the position of the handling handle 2), and forming a label outline 38 in the first frontal layer 8 so that the hanging handle 2, with the label formed, protrudes at least partially overhanging beyond the label outline 38.

According to an alternative embodiment of the method, in step vii) the separation of the hanging handle 2 and of at least one secondary label 34 in a different zone 36 occurs in a direction opposite with respect to the forming of the label outline 38 in the first frontal layer 8 so that the hanging handle 2 is placed, with label 1 formed, partly overhanging beyond the label outline 38.

In accordance with a further embodiment, in step vii) separating and forming are die-cutting steps.

For example, the secondary labels 34 may be a plurality of secondary labels 34.

According to an embodiment, the different zone **36** may be superimposed only on the release promoter of the first layer **12** (when two layers of promoter are provided).

According to a variant, the hanging handle **2** is partly overhanging and extends beyond a label width **100**. In other words, such handle protrudes outside the first frontal layer **8**.

In an embodiment, the first laminated material **4** and/or the second laminated material **20** are initially in the form of a strip, which extends along a prevailing development direction X, X'.

According to a further embodiment, the first frontal layer **8** and/or the second frontal layer **28** may comprise or consist of a plastic film.

According to a yet further embodiment, the first frontal layer **8** and/or second frontal layer **28** may have an average density of about 50-500 g/m², optionally 70-300 g/m², e.g. about 150 g/m².

In a variant, the frontal surface **10** of the first frontal layer **8** and/or a frontal surface **94** of the second frontal layer **28** are essentially planar and are optionally printable. In particular, one or both of these surfaces are configured so that graphic layers **56**, **58** can be distributed and adhere to them.

At least part of the frontal surface **10** of the first frontal layer **8** will, therefore, remain visible on a bottle when label **1** is applied to it, specifically by virtue of the transparency of the second frontal layer **28**.

According to an embodiment, the backing layer **6** serves as a releasable support for the completed label **1** and not only for the first frontal layer **8**.

According to an embodiment, the second frontal layer **28** is only partially opacified at the hanging handle **2** to reveal its presence, according to an embodiment without concealing the first graphic layer **56** superimposed on the first frontal layer **8**.

In other words, the partial opacification of the second frontal layer **28** allows, on the one hand, identifying the first graphic layer **56** (by virtue of the partial transparency of such layer **28**), and, on the other hand, identifying the hanging handle which is partially superimposed on the first graphic layer **56** (by virtue of the opaque component, partially impervious to light, of such layer **28**).

According to an embodiment, at the secondary label **34**, the label **1** comprises an opaque contrast layer **104** (e.g. see FIG. 13 or FIG. 15), superimposed on the second frontal layer **28** to substantially eliminate its transparency, at least a second graphic layer **58** superimposed on the opaque contrast layer **104** and at least a protective layer **106** of the second graphic layer **58**, at least partially transparent to light.

As a result, the opaque contrast layer **104** is a layer configured to opacify the transparency of the second frontal layer **28**, and further to act as a background and create contrast with the second graphic layer **58**.

The protective layer **106** is superimposed on the second graphic layer **58** (and preferably also on the opaque contrast layer **104**) so that the abrasive phenomena which occur when the label is applied to a bottle do not remove or smudge the second graphic layer **58**, or the opaque contrast layer **104** and second graphic layer **58** (according to the variant).

For example, for a dark or black second graphic layer **58**, the opaque contrast layer **104** may be a soft and/or neutral color, e.g. white.

According to an embodiment, the protective layer **106** is applied at least over the second graphic layer **58** using a flexographic method.

According to an embodiment, the protective layer **106** is applied at least over the second graphic layer **58** by a method other than a flexographic method.

According to an embodiment, the protective layer **106** is applied with a thickness of at least 1 µm or more.

According to an embodiment, the protective layer **106** delimits a writable surface **108** through an ink writing instrument, e.g. a ballpoint pen (jotter), or with inline markings, e.g. heat transfer.

10 In other words, the protective layer **106** performs the dual function of protection (as discussed above) and of writable substrate to annotate customized information on the secondary label **34**.

According to an embodiment, the second frontal layer **28** 15 is opacified through a pigment or color mixed with a release promoter substance of a layer of release promoter **12**, **18**.

According to a particularly advantageous embodiment, the first laminated material **4** and a precursor **22** of the second laminated material **20** comprise corresponding or 20 substantially identical layers. A definition of the term "identical" is given in the following description.

In an embodiment, such layers comprise, mutually superimposed, a backing layer **6**, a de-adhesive layer **24** (e.g. silicone-based), an adhesive layer **26**, **26'** and a first frontal layer **8**/second frontal layer **28**. According to such variant, step iv) comprises a step of separating, and optionally discarding, the backing layer and the de-adhesive layer of the precursor **22** upstream of step v).

During the optional step vi), the second layer of release 30 promoter **18** is then solidified (e.g.: cured) in contact with the adhesive layer **26'**, so as to bond such layers, and optionally so that the adhesive layer cannot perform its adhesive function as it is at least partially covered (and therefore rendered inert) by the second layer of solid release promoter **18**.

In other words, according to such variant, the second layer 35 of release promoter **18** works by "transfer" because, although it covers the first layer of release promoter **12**, the second layer of release promoter **18** transfers to the adhesive layer **26'** to make it inert in step vi).

In a further embodiment, the solidification step comprises a step of solidifying or cross-linking through electromagnetic radiation, e.g. UV radiation, or thermal radiation.

For example, step vi) may take place upstream of step vii).

45 According to a variant, the hanging handle **2** comprises at least one gripping portion **30** in which—in step iii)—the handle zone **16** also extends at such gripping portion **30**.

In the embodiments shown, the hanging handle **2** and, if 50 present, the gripping portion **30** comprises a portion protruding from an optionally curved outer edge **32** of the handle **2**. For example, the protruding portion is not in adhesive contact with the first frontal layer **8**, either by virtue of the double layer of the release promoter or because of its overhanging position with respect to it.

55 According to a further variant, step vii) comprises at least one sub-step of creating at least one creasing line **42**, **44** on the second frontal layer **28**, in order to deform the second frontal layer **28** and facilitate lifting of a portion, e.g. a peripheral portion, of the secondary label **34** and/or the hanging handle **2**. According to an embodiment, the creasing line **44** is made at the gripping portion **30** to lift a peripheral portion.

In a variant, step vii) comprises at least a first step of die-cutting-creasing **82**, and optionally a second step of die-cutting **84**, described hereinbelow.

According to an embodiment, step vii) is carried out outside the free zone **14**, so that in the zone **14** the second

frontal layer 28 creates a single anchoring foot 46 of the hanging handle 2, from which a pair of arms 48, 48' mutually connected in a ring extend.

According to a further embodiment, during step ii) and/or step iii), the first frontal layer 8 and/or the first (or only) layer of release promoter 12 are partially covered with one or more protective masks (not shown) which prevent the coating of some zones 52, 50 with the first layer of release promoter 12 and/or the second layer of release promoter 18, to modulate the separation force of an edge 32 (e.g. the outer edge) of the hanging handle 2 and/or a lifting portion 54 of the secondary label 34.

By way of example, at least one protective mask may comprise approximately punctiform protective elements, spaced along the extension of the edge 32 and/or the lifting portion 54 with predefined density.

As regards such density, it will be commensurate with the size of handle 2 and secondary label 34 and to the nature of the adhesive layer 26'.

According to a variant, the second frontal layer 28 is at least partially transparent to light to reveal an optional first graphic layer 56 distributed on the first frontal layer 8 (in particular upstream of step ii), e.g. as shown in FIG. 1). In a further variant, a layer of release promoter (e.g. the second layer of release promoter 18) comprises at least one pigment or color to make apparent (i.e. to reveal the presence of) at least part of the hanging handle 2.

Specifically, the pigment or color may be mixed with the release promoting substance of the layer of release promoter 18 (e.g. the second layer).

According to an embodiment, step vii) is followed by at least one step of scrap removing 60 in which, outside the hanging handle 2 and/or secondary label 34, the second frontal layer 28 and the first frontal layer 8 in its sole part, die-cut and placed under the portion of the hanging handle 2 that will be overhanging, is taken as continuous scrap 62, to create a lifting step 64 about the hanging handle 2 and/or secondary label 34 and to make a part of the overhanging hanging handle 2.

The aforesaid objectives are also achieved through a label 1 with a hanging handle 2 as described below.

Since a variant of the label provides manufacturing by the previous method, even where not expressly stated, the label may comprise any characteristic that can be inferred—from the point of view of the process—from the description above.

According to an embodiment, the label 1 comprises: a first laminated material 4 comprising a backing layer 6 and a first frontal layer 8 joined in a releasable manner; at least one layer of release promoter 12, 18, which coats a frontal surface 10 of the first frontal layer 8 leaving free a zone 14 from which the layer 12, 18 of release promoter is missing; an optional second layer of release promoter 18, which covers with registration a handle zone 16 of a first layer of release promoter 12; a second laminated material 20 comprising a second frontal layer 28, optionally transparent to light, and an adhesive layer 26', the second laminated material 20 being joined to the first laminated material 4 so that the adhesive layer 26' adheres at least to the free zone 14; wherein at least the thickness S1 of the second laminated material 20 delimits a hanging handle 2 at the handle zone 16, a secondary label 34 in a different zone 36, and wherein the first frontal layer 8 forms a label outline 38.

Optionally, the second layer of release promoter 18 is solidified in contact with the adhesive layer 26', to bond the layers 18, 26'.

According to a variant, the hanging handle 2 comprises at least one gripping portion 30, wherein the handle zone 16 also extends at such gripping portion 30.

According to a further variant, the second frontal layer 28 delimits at least one creasing line 42, 44 to facilitate lifting of a portion, e.g. a peripheral portion, of the secondary label 34 and/or the hanging handle 2.

According to a yet further variant, in the free zone 14, the second frontal layer 28 comprises a single anchoring foot 46 of the hanging handle 2, from which a pair of arms 48, 48' mutually connected in a ring extends.

Optionally, the pair of arms 48, 48' may be rotated with respect to the anchoring foot 46 (around a rotation axis R, in accordance with an embodiment, common to both arms), to allow the handle to be carried folded out of the label, and to act as hanging element of a bottle associated with it, in an upside-down position.

According to an embodiment, the second frontal layer 28 is at least partially transparent to light to reveal an optional first graphic layer 56 distributed on the first frontal layer 8.

According to an embodiment, the second frontal layer 28 is only partially opacified at the hanging handle 2 to reveal its presence without concealing the first graphic layer 56 superimposed on the first frontal layer 8.

According to an embodiment, at the secondary label 34, the label 1 comprises an opaque contrast layer 104, superimposed on the second frontal layer 28 to substantially eliminate its transparency, at least a second graphic layer 58 superimposed on the opaque contrast layer 104 and at least a protective layer 106 of the second graphic layer 58, at least partially transparent to light.

Optionally, a layer of release agent (e.g. second layer 18) may comprise at least one pigment or color to make apparent at least one part of the hanging handle 2, according to a variant without concealing the first graphic layer 56.

According to an embodiment, outside the hanging handle 2 and/or secondary label 34, the second frontal layer 28 is missing, to create a lifting step 64 about the handle and/or such secondary label 34.

According to an embodiment, the protective layer 106 is applied at least over the second graphic layer 58 using a flexographic method.

According to an embodiment, the protective layer 106 is applied with a thickness of at least 1 µm or more.

According to an embodiment, the frontal surface 10 of the first frontal layer 8 is coated with a first 12 and a second 18 mutually superimposed layers of release promoter outside the secondary label 34.

The manufacturing method diagrammatically shown in FIG. 1, in which the manufacturing direction F1, F2 extends from left to right according to the orientation of the arrows, will now be illustrated by way of example only.

At first, a first laminated material 4 and a precursor 22 of a second laminated material 20 are fed from two separate feeding reels, indicated by reference numerals 66, 68.

According to an embodiment, the first laminated material 4 and the precursor 22 are identical materials, or corresponding materials, fed from the two different reels 66, 68.

In the present description, the term “identical” indicates a material with the same laminations, although different layers may, in principle, be chemically different between the first laminated material and the precursor (and therefore also between the first and second laminated material).

The “common” laminated material is optionally formed by the following layers, superimposed from bottom to top in the order specified below: a backing layer **6**, a de-adhesive layer **24** (e.g. silicone), an adhesive layer **26**, **26'** and a first frontal layer **8**/second frontal layer **28**, e.g. printable.

The aforesaid layers are mutually superimposed completely, with a substantially full surface, or in a prevalent manner.

The backing layer **6** and the de-adhesive layer **24** are immediately removed from the precursor **22** coming from the reel **68**. They are separated and wound back onto a reject reel **70**, while the adhesive layer **26'** and the second frontal layer **28** form the second laminated material **20** which will continue towards a joining point **72** in the direction **F1**.

According to an embodiment, at the arrow **102** (i.e. after separation), on the second laminated material **20**, the opaque contrast layer **104** superimposed on the second frontal layer **28**, the second graphic layer **58** superimposed on the opaque contrast layer **104** and the protective layer **106** of the second graphic layer **58** are distributed/printed in the area in which the secondary label **34** will be created.

According to a variant, a first graphic layer **56** (e.g. containing product information) is distributed/printed on the first laminated material **4** coming from the reel **66** and, a single layer of release promoter, or a first **12** and a second **18** layers of release promoter, e.g. silicone paint, are superimposed over the first graphic layer **56** to obtain the intermediate material **74**.

The first or single layer of release promoter **12**, in contact with the first graphic layer **56**, occupies a smaller surface area than the frontal surface **10** of the first frontal layer **8**. More precisely, the first or single layer of release promoter **12** is applied to leave a free zone **14** from which the first layer of release promoter **12** is missing.

For example, the layer of release promoter **12** may be applied in a retracted position with respect to a first longitudinal edge **76** of the first laminated material **4**, so as to offer a free surface to the second laminated material **20**—which will be superimposed on the intermediate material **74** at the joining point **72**—onto which an anchoring foot **46** of the hanging handle **2** made from the second laminated material **20** can firmly adhere.

Instead, the optional second layer of release promoter **18**, superimposed and optionally in contact with the first layer of release promoter **12**, will be applied with registration with the preset position of the hanging handle, in liquid or semi-liquid form.

In the present description, the term “registration” means an application on a layer with a specific shape, in this case substantially corresponding to the surface of the hanging handle.

Appropriately shaped masks may be used for this purpose, covering the underlying first layer of release promoter **12** to prevent depositing the second layer of release promoter **18** outside the profile of the handle **2**.

Regarding the expression “semi-liquid” used above, it is worth noting that, in this description, the term “semi-liquid” means any liquid substance capable of flowing, even with low fluidity, in particular at the working temperature of step **iii**.

By way of non-exhaustive example, such term may mean any viscous, gelatinous and/or pasty substance.

According to a variant, the hanging handle **2** is made apparent through a partial opacification/pigmentation/coloring of the second frontal layer **28**, which creates a visual or chromatic separation from the first frontal layer.

Optionally, the partial opacification/pigmentation/coloration of the second frontal layer **28** may be achieved through the characteristics of the layer of release promoter **18**, which specifically comprises a pigment/color.

For example, such pigment or color may be mixed with the release promoter substance of the second layer of release promoter **18** or placed on the surface of the second layer of release promoter **18** facing the second frontal layer **28**.

The function of the optional second layer of release promoter **18** is, of course, to neutralize adhesion power of the adhesive layer **26'** of the second layer material **20**, or make it almost completely inert, through the transfer mechanism described above, to facilitate lifting of the handle (alone).

The intermediate material **74** and the second laminated material **20** are then joined at the joining point **72**, being joined and pressed by a pair of rollers **78**, **80**, thus creating the laminated material **40**.

After the manufacturing of the laminated material **40**, the optional second layer of release promoter **18** is then solidified in contact with the adhesive layer **26'**, e.g. by UV radiation, to bond such layers **18**, **26'** and to make the adhesive layer “passive” **26'**.

At a later step, the method continues with a first step of die-cutting-creasing **82**, and a second step of die-cutting **84**, each followed by a step of eliminating production scraps **62**, **86**.

During the first step of die-cutting-creasing **82**, a tool configured to fold/crease, without scoring, the second frontal layer **28** at the hanging handle **2** (in particular at the gripping portion **30** thereof, when provided) and/or the lifting portion **54** of a secondary label **34** may optionally be used.

As far as the position of the secondary label **34** is concerned, the latter will, in accordance with an embodiment, be positioned above the first layer of release promoter **12** only, because the adhesive power of the secondary label **34** must not be eliminated (or rather must not be made inert) entirely, as in the case of the hanging handle.

In such manner, through the transfer and solidification of the optional second release promoter in (semi-)liquid form, it will be possible to make the adhesive layer **26'** at the hanging handle **2** inert, without conditioning the adhesive power of the secondary label **34**.

In all other portions, other than the creasing lines **42**, **44**, the die-cutting depth **82**, i.e. the cutting depth of the laminated material **40**, will extend until at least the second frontal layer **28**, and optionally also the second layer of release promoter **18**, are scored, possibly without notching the layer **12** underneath it.

The scoring depth of the coupled material **40** in this first step **82** is indicated by the arrows **90** in FIGS. **12**, **13**.

The profile of the first step of die-cutting-creasing **82** is such as to create, both internally and externally, the shape of the handle, and is such as to cut out the second frontal layer **28** in part (e.g.: along a pair of optionally orthogonal sides **97**, **98**; FIG. **14**) about the perimeter of the secondary label **34**.

The portion removed as continuous scrap **62** downstream of the first step of die-cutting-creasing **82** is, therefore, a ribbon of complementary shape to the lifting step **64** shown in FIG. **17**, as well as the portion of the first frontal layer which was placed under the portion of the hanging handle **2** which is left overhanging.

During the second step of die-cutting **84**, a cutting tool is used, configured to score the laminated material **40** from its surface **94** at least up to the first frontal layer **8**, and optionally up to the adhesive layer **26** of the original

11

laminated material 74, as diagrammatically shown by the arrows 88 schematically shown in FIG. 15.

In any case, within the exposed surface of the label 1, this second step of die-cutting 84 will cut the label outline 38 about the first frontal layer 8 and the hanging handle 2.

FIG. 13 shows the position of the secondary label 34 in relation to the first (or only) layer of release promoter 12.

For the secondary label 34, the single or first layer of release promoter 12 may be specially modulated, by depositing the promoter only in some zones, thus preventing the formation of an inert layer under the adhesive layer of the secondary label.

In this regard, protective masks may be used to prevent covering certain zones 52 (FIG. 5) of the first frontal layer 8. A similar expedient may be used to prevent coating some zones 50 below the second frontal layer with the second layer of release promoter 18, to obtain a handle which is dry and not sticky to the touch.

On the contrary, in FIG. 12, the optional double layer 12, 18 of release promoter under the hanging handle 2 in the portions outside the anchoring foot 46 can be observed.

The second step of die-cutting 84, therefore, has the function of creating the separation between adjacent labels 1, and the continuous scrap 86 will be shaped as a ribbon in which empty seats are obtained (rectangular seats according to the shapes shown), of a shape complementary to the label outline 38 of each label, interspersed with separating partitions corresponding to the material removed to divide the labels 1.

After eliminating the second continuous scrap 86, the labels 1 have been created and can be wound on a collection reel 92 (FIG. 1).

Innovatively, the method and label of the present invention allow brilliantly overcoming the drawbacks of the prior art.

More precisely, the method and handle of the present invention allow obtaining in a simple manner a handle which extends well beyond the label outline 38.

Furthermore, the method and handle of the present invention allow modulating transparencies and opacity of the second frontal layer, so as not to conceal the first graphic layer, to show the position of the hanging handle, to suppress the transparency of such layer to the secondary label to achieve a contrast for the second graphic layer and to protect the second graphic layer.

According to an embodiment, the method and label of the present invention allow obtaining a label with handle in a single production step, without having to perform special operations (e.g. such as gluing the handles one-by-one), in a simple, reliable and cost-effective manner.

According to an embodiment, the method and label of the present invention allow obtaining a secondary label which can be written, thus allowing it to be handwritten according to needs.

According to an embodiment, the method and label of the present invention provide an innovative system of coating in liquid or semi-liquid form, and subsequent solidification or targeted cross-linking, to create a passive layer by transfer under the handle.

Furthermore, the handle is easy to handle because it is dry to the contact.

According to an embodiment, the method and label of the present invention allow achieving an important economy of production, not only by virtue of raw materials involved in manufacturing.

12

According to an embodiment, the method and the of the present invention allow obtaining an excellent grip on the handle and/or secondary label.

According to an embodiment, the method and label of the present invention provide an extremely cost-effective way to locate the handle without covering the underlying graphics.

According to an embodiment, the method and the label of the present invention allow creating specific ergonomic portions to ensure easy interaction with the user.

According to an embodiment, the risk of tearing the handle or one of its arms from the foot is virtually absent under normal conditions of use.

According to an embodiment, the method and the label of the present invention provide an additional system to regulate the adhesive power of the portions which can be lifted from the plane of the label.

According to an embodiment, the method and the label of the present invention allow obtaining labels which can be applied as a continuous strip, so that their application on bottles in automated processes is simplified.

According to an embodiment, the method of the present invention is cost-effective, and the label described can be produced at a low cost.

In order to meet specific needs, those skilled in the art may make variants or substitutions of elements with functionally equivalent ones to the embodiments of the method and label above.

Such variants are also contained within the scope of protection as described and claimed herein.

Furthermore, each variant described as belonging to a possible embodiment may be implemented independently from the other described variants.

 The invention claimed is:
 1. A method for manufacturing a label with a hanging handle, the method comprising:
 i) providing a first laminated material comprising a backing layer and a first frontal layer joined in a releasable manner, wherein said first frontal layer comprises a frontal surface;
 ii) coating said frontal surface of the first frontal layer with at least one layer of release promoter, leaving a free zone in which said at least one layer of release promoter is missing;
 iv) providing a second laminated material comprising a second frontal layer and an adhesive layer, wherein said second laminated material has a predefined thickness;
 v) joining said first laminated material and said second laminated material to form an assembled component or coupled material so that the adhesive layer of the second laminated material adheres at least to the free zone of the first laminated material; and
 vii) cutting a hanging handle in a handle zone of said second laminated material only to the inside of the thickness of the second laminated material, leaving said first frontal layer intact; cutting at least one secondary label in a secondary label zone different from said handle zone only within the thickness of the second laminated material; forming a label outline in the first frontal layer, avoiding cutting the hanging handle and removing a portion of said first frontal layer thus 40 creating a cavity that arranges a handle portion of said hanging handle, with the label formed, protruding overhangingly beyond said label outline, overhanging said cavity. 45
 2. The method of claim 1, wherein said second frontal layer is transparent to light. 55
 3. The method of claim 1, wherein:
 said second frontal layer is opacified only partially at the hanging handle to reveal the hanging handle without concealing a first graphic layer superimposed on the first frontal layer and wherein, at the at least one secondary label, said label comprises an opaque contrast layer, superimposed on the second frontal layer to eliminate its transparency, a second graphic layer superimposed on the opaque contrast layer and a protective layer of the second graphic layer, at least 60 partially transparent to light; and wherein

14

- said protective layer is applied over the second graphic layer by a flexographic method, with a thickness of at least 1 μm or more.
 4. The method of claim 3, wherein said protective layer 5 delimits a writable surface through an ink writing instrument or inline markings.
 5. The method of claim 1, wherein the second frontal layer is opacified through a pigment or color mixed with a release promoter substance of the at least one layer of release promoter.
 6. The method of claim 1, wherein in step vii) cutting the hanging handle in the handle zone and the at least one secondary label in the secondary label zone occurs in a direction opposite to forming the label outline in the first frontal layer so that the hanging handle is placed, with the label formed, partly cantilevered beyond said label outline. 10
 7. The method of claim 1, wherein the first laminated material and a precursor of the second laminated material comprise corresponding or identical layers which comprise, 20 mutually superimposed, a backing layer, a de-adhesive layer, an adhesive layer and a first/second frontal layer, and wherein step iv) comprises a step of separating and discarding the backing layer and the de-adhesive layer of said precursor upstream of step v).
 8. The method of claim 1, wherein step vii) is carried out outside the free zone, so that in said free zone the second frontal layer creates a single anchoring foot of the hanging handle, from which a pair of arms mutually connected in a ring extend. 25
 9. The method of claim 1, wherein step ii) comprises a step of coating with a first and a second mutually superimposed layers of release promoter outside the at least one secondary label.
 10. A label with a hanging handle made using the method 30 of claim 1, said label comprising:
 a first laminated material comprising a backing layer and a first frontal layer joined in a releasable manner, wherein said first frontal layer comprises a frontal surface;
 at least one layer of release promoter coating the frontal surface of the first frontal layer leaving free a zone in which said at least one layer of release promoter is missing; and
 a second laminated material comprising a second frontal layer and an adhesive layer, said second laminated material being joined to the first laminated material so that the adhesive layer adheres at least to the free zone, wherein the second frontal layer has a predefined thickness; 35
 wherein said second frontal layer delimits the hanging handle and a secondary label in a secondary label zone, and wherein the first frontal layer forms a label outline leaving said hanging handle with a handle portion protruding at least partially overhanging beyond said label outline outside the first frontal layer directly facing said backing layer, thus forming a cavity in which a portion of said first frontal layer has been removed, said handle portion overhanging said cavity.
 11. The label of claim 10, wherein said second frontal layer is transparent to light. 40
 12. The label of claim 10, wherein:
 said second frontal layer is opacified only partially at the hanging handle to reveal the hanging handle without concealing a first graphic layer superimposed on the first frontal layer and wherein, at the secondary label, said label comprises an opaque contrast layer, superimposed on the second frontal layer to eliminate its

15

transparency, a second graphic layer superimposed on the opaque contrast layer and a protective layer of the second graphic layer, at least partially transparent to light; and wherein
said protective layer is applied over the second graphic 5
layer by a flexographic method, with a thickness of at
least 1 μm or more.

13. The label of claim **12**, wherein said protective layer
delimits a writable surface through an ink writing instrument
or inline markings. 10

14. The label of claim **10**, wherein said second frontal
layer is opacified through a pigment or color mixed with a
release promoter substance of the at least one layer of release
promoter.

15. The label of claim **10**, wherein in the free zone, the 15
second frontal layer creates a single anchoring foot of the
hanging handle, from which a pair of arms mutually con-
nected in a ring extend.

16. The label of claim **10**, wherein the frontal surface of
the first frontal layer is coated with a first and a second 20
mutually superimposed layers of release promoter outside
the secondary label.
